UNITED STATES PATENT OFFICE

2,049,090

SHEDDING MECHANISM FOR LOOMS

Hugo Stäubli, Zurich, Switzerland, assignor to
Gebr. Stäubli & Co., Horgen, Zurich, Switzerland

Application April 27, 1934, Serial No. 722,770

16 Claims. (Cl. 139—77)

The invention relates to shedding mechanisms for looms, especially shedding mechanisms of the so called gem head type as represented for instance in my United States Letters Patent No. 1,886,133 dated August 23, 1932. Already in the mechanism shown and described in said Letters Patent pattern-cards of Verdol-paper or like thin, light material can be used and the pick reading may be effected by means of a pick-reading mechanism constructed in such a manner that at the return-movement of the pattern-card cylinder picks already woven in are released in correct sequence.

The present invention has for its object to improve said pick-reading mechanism with a view to reduce the number of moving parts and to render it more effective.

On the accompanying drawings

Fig. 1 illustrates an elevation of a shedding mechanism constructed according to the present invention, this elevation being taken from the outside of the machine frame.

Fig. 2 shows a similar elevation of the same shedding mechanism but taken from the inside of the machine frame, some parts being shown in section.

Figs. 3 and 4 show details hereinafter referred to.

For sake of clearness certain known parts are omitted on the drawing to better illustrate the main difference between the pick-reading mechanism according to the present invention and that shown and described in my prior specification cited above.

1 represents the endless continuous pattern-card consisting of Verdol-paper or other thin light material, 2 is the cylinder supporting this pattern card. On the shaft 3 of this cylinder is mounted fixed a toothed wheel 4 which is intermittently driven from a shaft 6 by means of a cam 5 temporarily engaging with the notches provided on the periphery of the wheel 4.

On a supporting shaft 7 mounted in the machine frames 12 like as the shafts 3 and 6, there are loosely mounted directly side by side rocking levers 8, one for each harness shaft. To each of these rocking levers 8 is pivotally connected a wire or rod 9 disposed above the cylinder 2 and having its rear end formed as a hook 10. From each rod 9 there hangs loosely a pick reading needle 11 by means of an eye vertically above the cylinder shaft 3. Below all rods 9 there extends a lifting bar 13 which is supported by two levers 42 fixed on the shaft 7 or on another suitable shaft, this lifting bar 13 serving to hold the pick-reading needles 11 far off the cylinder 2 during the movement thereof. The swinging motion of the levers 42 is produced by the shaft 6 by means of a cam 43 acting upon roller 44 mounted on another arm of the lever 42, see Fig. 4. By means

of a hand lever or the like (not shown) mounted on the supporting shaft 7 or other shaft supporting the lifting bar 13, this latter may be swung upwardly at any convenient time, for instance, when the cylinder 2 shall be taken back by hand in case the releasing of a greater number of picks is required.

In each of two horizontal slots 15 in each machine frame 12, there is loosely mounted a bar 16, 17 respectively, one above the other with a little vertical distance one from another.

The bar 16 is pivotally connected with an arm 18 the front end of which forms a fork 19 embracing with its legs the shaft 6 in such a manner that the arm 18 is free to make a horizontal reciprocating motion at right angle to the shaft 6.

Fixed on the shaft 6 are two cams, 20, 21, one of which, 20, bears against a roller 22 mounted on the sliding arm 18 and held in constant contact with the cam 20 by a pull spring 41 one end 20a of which is fixed on the arm 18, and the other end on a pin 45 mounted on a lever 23 fixed on the shaft 7.

The cam 21 bears against a roller 33 mounted on the lever 23. Loosely mounted on said pin 45 there is an arm 46 the other end of which being pivotally connected with the upper bar 17, the spring 41 holding the roller 33 in constant contact with the cam 21.

The upper end of each rocking lever 8 loosely mounted on the supporting shaft 7 is provided with a roller 14 adapted to move below and in the plane of a plate 30 fixed on one of a series of vibrator-levers 25 fulcrumed on a rod 26 fixed in the machine frames 12. Each of said vibrator levers 25 supports on a pivot extending from the side thereof, a vibrator-gear 27, having a crank-pin 28 adapted to be turned in one and then in an opposite direction by one or the other of the continuously-rotating cylinder-gears 38, 39. Each crank-pin 28 has pivoted to it one end of a connector 29 the opposite end of which is connected in known manner with a harness-controlling lever 31. The vibrator levers 25 and the above mentioned parts connecting them with the levers 31, as well as these levers themselves and the gears 38, 39 are in substance known from my above cited prior specification.

Fig. 2 shows in full lines the parts 8, 9, 25, 27 in that position which they occupy when the associated pick-reading needle 11 rests upon the full part of the pattern-card 1, while the dash-dotted lines represent said parts after the corresponding pick-reading needle 11 has dropped into a hole of the pattern-card 1.

Starting from the position shown in full lines whilst the shaft 6 rotates in clock-wise direction, the highest point of the cam 21 runs off from the roller 33 so that the lever 23, by the

action of the spring 41, pushes to the left the push bar 17. The supporting blade 32 fixed at the underside of the bar in order to support the hook 10 on the free end of the rod 9 at certain periods slides off from beneath the hook 10 of the rod. At the same time the highest point of the cam 20 slides away from the roller 22 so that the arm 18 and with it the bar 16 are drawn to the right by the spring 41.

10 During this part of rotation of the shaft 6 the lifting bar 13 is lifted to maintain in raised position the rods 9 which have been supported by the blade 32 and to raise the other rods 9 which laid on the drawing bar 16. While 15 thus all picking-needles 11 are removed from the pattern-card 1 the cylinder 2 receives a motion corresponding to one tooth of the wheel 4 by the engagement of the cam 5 with this wheel. Now the lifting bar 13 is lowered again to allow 20 the picking-needles 11 to read the following pick. The drawing bar 16 is then in its outmost position to the right, the push bar 17 in its outmost position to the left and each bar is ready to begin its movement opposite to that indicated 25 by the arrows in Fig. 2.

Assuming now the pick-reading needle 11 which depends from the rod 9 shown in full lines in Fig. 2 be dropped into a hole of the pattern-card 1. Then said rod 9 lies upon the bar 16 30 which is now moved to the left in consequence of the cam 20 beginning to act upon the roller 22 supported by the sliding fork 19. By means of its hook 10 said rod 9 is withdrawn by the back-moving bar 16 and thereby the rocking 35 lever 8 to which the rod 9 is connected is rocked from the position shown in full lines in Fig. 2 to the left into the position represented by dash-dotted lines. During this rocking motion of said lever 8 its roller 14 engages with the lower edge 40 of the plate 30 on the corresponding vibrator-lever 25. Consequently this lever is turned upwardly to the position shown in Fig. 2 by dash-dotted lines whereby the harness-controlling lever 31 is turned substantially as described in my 45 prior specification cited above and in the prior specifications mentioned there.

When the left hand extremity of the slot 34 in the gear 27 reaches the pin 35 on the vibratory-lever 25, the rotation of the gear 27 stops. 50 At this time a long toothless space 36 on the periphery of the gear 27 lies opposite the gear 38 so that the gear 27 will not rotate although the gear 38 continues its rotation. Thus the associated harness-shaft rests in its raised position 55 whilst the bar 16 makes its return movement indicated by the arrow in Fig. 2.

If at the next rotation of the shaft 6 the same pick-reading needle 11 drops again into a hole of the pattern-card 1 the corresponding harness-shaft rests in its raised position.

If however at said second rotation of the shaft 6 and the corresponding pick-reading action the same pick-reading needle 11 which had previously dropped into a hole of the pattern-card 1 65 does not find a hole but rests upon the pattern-card, the hook 10 of the rod 9 remains in the path of the push bar 17 and is pushed backwards thereof at the next forward stroke (to the right) of said bar. Consequently the associated 70 rocking lever 8 will be pushed to the right and its roller 14 runs off from the plate 30 so that the vibrator-lever 25 with the gear 27 returns to its lower position, shown in full lines on Fig. 2. To limit said outward motion of the lever 8 a cross rod 40 is provided.

If in the following rotation of the shaft and pick-reading action the same pick-reading needle 11 which on the previous time had not dropped into a hole of the pattern-card does again not find a hole thereon the associated parts 8, 9, 10, 25, 27 rest in their position shown in Fig. 2 in full lines and the associated harness-shaft will rest in its lowered position.

It will thus be seen that in each case where a pick-reading-needle 11 comes to the same position in two subsequent pick-reading actions there will be no alteration in the position of the associated harness-shaft. In this way the operation of the shedding-mechanism is much simplified and the number of parts which are to be 15 acted upon is much reduced.

The cylinder 2 is adapted to be rotated backward in known manner in order, for instance, to release picks which have already been interwoven. For reversing the cylinder the means 20 shown in my prior specification 1,886,133 may be used.

A pick-reading mechanism similar to that represented and described above may, with suitable alterations, be used in connection with 25 shedding mechanisms wherein a harness-shaft is actuated upon when the associated pick-reading needle does not drop into a hole of the pattern-card but upon a full part thereof. Further the arrangement may be made suitable for 30 the use of pick-reading needles which are not disposed vertically above the axis of the pattern-card cylinder but which act from the side thereof.

What I claim is:

1. In a shedding mechanism for looms, the combination of a pattern-card of Verdol-paper or other thin light material, with a rotatable cylinder which is not reciprocated and acts to support said pattern-card, pick-reading needles 40 adapted to be brought in engagement with said pattern-card, a vibrator-lever for each of said pick-reading needles, a movable rocking lever for each vibrator-lever for controlling the position thereof, reciprocating bars, a single movable rod connected with each of said rocking levers and adapted to be engaged by one or the other of said bars according to the position of the associated pick-reading needle relatively to the pattern-card the arrangement being such that the position of said rocking lever relatively to the associated vibrator lever is not altered as the associated pick-reading needle comes to the same position in subsequent pick-reading actions.

2. In a shedding mechanism for looms, the combination of a pattern-card with a rotatable but not reciprocating cylinder supporting it, a series of pick-reading needles adapted to be brought into engagement with said pattern-card, a single movable rod for each of said needles, a 60 pair of reciprocating bars adapted to act upon said rods, a rocking lever connected with each of said rods and adapted to be actuated by one or the other of said bars and the associated needle rod according to the position of the latter relatively to the pattern-card, a vibrator lever disposed above each of said rocking-levers and controlled thereby as to its position, a gear on this vibrator lever located between two cylinder-gears to alternately be brought in reach of one 70 or the other thereof according to the position of said vibrator lever, and a harness-controlling lever connected with said vibrator-gear.

3. In a shedding mechanism for looms, the combination of a pattern-card of Verdol-paper 75

- or other thin light material, a cylinder for supporting this pattern-card, a series of rods crossing said cylinder above thereof, a pick-reading needle depending from each of said rods above 5 said cylinder, a rocking lever for each of said rods and pivotally connected therewith, means for periodically allowing the pick-reading needles to come in engagement with the pattern-card and to be removed therefrom, two bars mounted 10 above one another and adapted to receive reciprocating motions in opposite direction and to shift thereby a determined number of said rods according to their position relatively to the pattern-card.
15. 4. In a shedding mechanism for looms, the combination of a pattern-card Verdol-paper or other thin light material with a rotatable but not reciprocating cylinder supporting this pattern-card, a series of rods disposed across and 20 above the cylinder, a pick-reading needle depending from each of these rods in the vertical axial plane of said cylinder, a series of rocking levers mounted on an axis parallel to the cylinder, each of these rocking levers supporting one end of 25 one of said rods, a bar extending beneath said rods across thereto and adapted to periodically lower and raise them all together in order to bring the pick-reading needles into and out of engagement with said pattern-card, two bars mounted one 30 above another at a certain distance and adapted to perform reciprocating motions in opposite direction and to shift thereby some of said rods in one or the other direction according to the position of the associated pick-reading needle 35 relatively to the pattern-card.
5. In a shedding mechanism for looms, the combination of an endless continuous pattern-card Verdol-paper or other thin light material with a rotatable cylinder mounted on a non-reciprocating axis and supporting said pattern-card, pick-reading needles adapted to be brought in engagement with said pattern-card, a vibrator-lever for each of said pick-reading needles, a connection of this vibrator lever with a harness-shaft, a movable rocking lever for each of said 40 vibrator-levers, a pull- and push-rod pivotally connected with this rocking lever, the position of this rod being determined by the position of the associated pick-reading needle relatively to 45 said pattern-card, means, independent from said cylinder, adapted to cause said needles to read a pick on the pattern-card, said cylinder being at rest; and two bars mounted one above another in suitable distance and adapted to reciprocate in opposite directions one relatively to the other, the above mentioned pull- and push-rods and therewith the arms supporting the associated vibrator levers being engaged by one or the other of said reciprocating bars or let at rest 50 according to the position of the associated pick-reading needle relatively to the pattern-card.
6. A shedding mechanism for looms, comprising a pattern-card Verdol-paper or other thin light material, a series of pick-reading needles, 55 a vibrator-lever for each of these needles, a gear on this vibrator-lever located between two cylinder-gears to alternately be brought in reach of one or the other thereof according to the position of said vibrator-lever, a harness-controlling lever connected with said vibrator-gear, a rocking lever adapted to support said vibrator-lever, a rod pivotally connected with this rocking-lever and extending over the pattern-card, a pick-reading needle depending from this rod 60 towards the pattern-card, means adapted to allow 65 or impart to said rod a swinging motion around its pivot on said rocking-lever to bring the pick-reading needle into and out of contact with the pattern-card, two reciprocating bars disposed in a suitable distance one above another, one or the other of these bars engaging with said rod according to the position of the associated pick-reading needle relatively to the pattern-card, the engagement resulting in a rocking motion of said rocking arm causing a movement of said vibrator-lever.
7. In a shedding mechanism for looms, the combination of a pattern-card of Verdol-paper or other thin light material, with a cylinder for supporting this pattern-card, a toothed wheel for 15 imparting partial movements to this cylinder, a series of pick-reading needles, a harness-controlling-mechanism comprising a vibrator lever for each of said needles, a rocking lever controlling the position of said vibrator-lever, a rod pivoted 20 to this rocking lever and supporting a pick-reading needle, two bars disposed one above the other near the free end of said rod, cams for moving these bars in such direction in which, according to the position of the pick-reading needle 25 relatively to the pattern-card, one or the other of said bars acts upon said rod and the associated rocking lever to move the vibrator-lever supported by this rocking lever, another cam mounted in such a position relatively to said two 30 cams as to give a partial movement to said toothed wheel and thereby to the cylinder at a moment where said bars are not actuated upon by their cams.
8. In a shedding mechanism for a loom, a 35 frame, a shaft fixedly but rotatably mounted therein, a cylinder for carrying an endless pattern card or Verdol-paper or other thin light material mounted on said shaft to rotate therewith, vibrating levers pivotally mounted in said frame, a supporting shaft mounted in said frame, a rocking lever mounted on said supporting shaft for each of said vibrating levers and supporting the latter, the lower surface of each of said vibrating levers being cam shaped whereby the 45 rocking of said rocking lever raises and lowers said vibrating lever and means for actuating said rocking levers including a reading needle so constructed and timed that upon the reading needle resting in the same position after successive steps 50 of the pattern card the rocking levers will retain the same position.
9. In a shedding mechanism for a loom, a 55 frame, a cylinder mounted on said shaft to rotate therewith, a toothed wheel fixedly mounted on said shaft, a pattern card supported on said cylinder, a driving shaft mounted in said frame, a cam on said driving shaft intermittently engaging said toothed wheel to rotate the same, a supporting shaft, rocking levers on said supporting shaft, a vibrating lever resting on each of said levers and each having a cam on its lower surface in the path of its rocking lever, said vibrating lever being pivotally supported from said frame whereby it will be raised and 60 lowered by the rocking of said arm, a rod pivotally attached to each said lever and having a hook at the end thereof, a pick reading needle suspended from said rod above the pattern card, angular levers on said supporting shaft, a 65 lifting bar supported by said angular levers and extending transversely of said frame beneath said rods, cams on said driving shaft for actuating said angular levers whereby the rods are raised to free the reading needle from contact 70
- 75

with the pattern card, two reciprocating bars slidingly supported in said frame at different horizontal levels and means transmitting motion from the driving shaft to reciprocate said bars, 5 the one moving in one direction and the other in the other direction, the upper reciprocating bar being at a height to engage and push the said rod when said reading needle rests on the surface of the pattern card and the lower reciprocating bar being at a height to engage and pull the rod when said reading needle finds a hole in the pattern card, the movements of said lifting rod, said reciprocating bars, and said cylinder being relatively so timed that upon the 10 reading needle resting in the same position with regard to said cylinder after successive steps of the latter, the rocking arms and hence the vibrating lever will remain at rest.

10. In a shedding mechanism for looms, the combination of a pattern-card of Verdol-paper or other thin light material with a rotatable but not reciprocating cylinder supporting said card, pick-reading needles adapted to be moved towards and away from said cylinder, a rocking 20 lever for each of these needles, a rod for each needle connecting said needle and said rocking lever, two movable members adapted to simultaneously reciprocate in opposite directions and to alternately actuate a certain number of said 25 rocking levers in opposite directions by means of said rods, according to the position of the associated needles relatively to the pattern-card cylinder, the reverse motion of the reciprocating members being without effect upon the rocking lever.

11. In a shedding mechanism for looms, the combination of a pattern card of Verdol-paper or other thin light material, with a rotatable but not reciprocating cylinder for supporting this 40 pattern card, pick-reading needles adapted to be moved towards and away from said cylinder, a rocking lever for each of these needles, two members adapted to simultaneously reciprocate in opposite directions, an intermediate member 45 between this rocking lever and said reciprocating members adapted to be brought into the path of one or the other of these members for the opposite parts of their movements to actuate the rocking lever in one or the other direction according 50 to the position of the associated pick-reading needle relatively to the pattern-card cylinder, the reverse motion of said members being without effect upon the rocking lever.

12. In a shedding mechanism for looms, the combination of a pattern-card of Verdol-paper or other thin light material, with a rotatable but not reciprocating pattern-card cylinder, pick-reading needles adapted to be moved towards and away from said cylinder, an individual holding 55 means for each of said needles, a rocking lever connected with said holding means, two reciprocating members adapted to alternately act upon said holding means in opposite directions according to the position of the associated needles relatively to the pattern-card cylinder to rock said 60 rocking lever, the reverse movements of said reciprocating members being ineffective for the rocking lever.

13. In a shedding mechanism for looms, the combination of a pattern-card of Verdol-paper or other thin light material, with a rotatable but non-reciprocating cylinder for supporting this 65 pattern-card, pick-reading needles adapted to be moved towards and away from said cylinder, a

holding member for each of these needles, a rocking lever connected with this holding member, two movable bars reciprocating in opposite directions to actuate a certain member of said rocking levers by means of said holding member according to the position of the associated pick-reading needles relatively to the pattern-card cylinder, the position of the rocking lever resting the same for two or more subsequent movements of said reciprocating bars in case where 10 the associated pick-reading needle finds its previous position relative to the pattern-card cylinder during subsequent pick-reading actions.

14. In a shedding mechanism for looms, the combination of a pattern-card of Verdol-paper or other thin light material, with a rotatable but not reciprocating cylinder which acts to support said pattern card, pick-reading needles adapted to be moved towards and away from said cylinder, a vibrator lever for each pick-reading needle, a 20 rocking lever for each of these vibrator levers, two movable bars reciprocating in opposite directions, a movable means for each pick-reading needle connected with one of said rocking levers and adapted to be actuated by one or the other 25 of said movable bars to be brought to or out of engagement with the associated vibratory lever according to the associated pick-reading needle relatively to the pattern-card, the position of the rocking lever relatively to the associated vibrator 30 lever being maintained if subsequent equal positions of the pick-reading needle relatively to the pattern card occur.

15. In a shedding mechanism for looms, the combination of a pattern-card of Verdol-paper or other thin light material, with a rotatable but not reciprocating cylinder for this pattern-card, a series of rocking levers, two bars located 35 one above another, a shaft, two cams fixed on this shaft and adapted to displace said bars in 40 opposite directions towards and away from said rocking levers, a rod pivotally connected with each of said rocking levers and extending above the pattern-card cylinder across the axis thereof in the direction towards said bars, a pick-reading 45 needle on each of said rods above said cylinder, means for bringing said rod into and out of the path of said bars according to the position of the associated pick-reading needle relatively to the pattern-card cylinder.

16. In a shedding mechanism for looms, the combination of a pattern-card of Verdol-paper or other thin light material, with a rotatable but not reciprocating cylinder for this pattern-card, a series of rocking levers, two bars located 55 one above another, a shaft, two cams fixed on this shaft, a sliding arm connecting one of said bars with one of said cams, a lever connecting the other of said cams with the other of said bars, the position of said cams relatively one to another 60 and to said sliding arm and lever being such that said cams act upon said two bars at the same time but in opposite directions, a spring connecting said sliding arm with said lever to hold these parts in constant contact with their cams 65 and to effect their return movement, a rod extending from each of said rocking levers towards said bars, a pick reading needle on each of these rods, means for moving these needles relatively to the pattern-card cylinder and to bring at the 70 same time said rod into the path of one or the other of said bars according to the position of the associated needle relatively to said cylinder.

HUGO STÄUBLI
